UNITED STATES PATENT OFFICE.

JOSEPH HARRINGTON, OF CHICAGO, ILLINOIS, ASSIGNOR TO GREEN ENGINEERING COMPANY, OF CHICAGO, ILLINOIS, A CORPORATION OF ILLINOIS.

TRAVELING-GRAVE FURNACE.

No. 898,101.

Specification of Letters Patent.

Patented Sept. 8, 1908.

Application filed February 23, 1906. Serial No. 302,609.

To all whom it may concern:

Be it known that I, JOSEPH HARRINGTON, a citizen of the United States, of Chicago, in the county of Cook and State of Illinois, have 5 invented certain new and useful Improvements in Traveling-Grate Furnaces; and I do hereby declare that the following is a full, clear, and exact description thereof, reference being had to the accompanying drawings, 10 and to the letters of reference marked thereon, which form a part of this specification.

This invention relates to adjustable means located between the rear end of the grate of an automatic stoking furnace and part of the 15 bridge wall of such furnace which overhangs the same to retard or hold back any unconsumed fuel and thereby insure complete combustion and to prevent the passage of air between the rear end of the grate and the bridge 20 wall.

The invention relates more especially to an adjustable, water-cooled bridge-piece or water-back of that kind shown in my prior application for United States Letters Patent, 25 Serial Number 226,417, filed February 28th, 1904. In the principal construction shown in my aforesaid application, the bridge-piece is pivotally mounted at the side walls of the furnace to swing toward and from the grate 30 on an axis of oscillation that maintains the bridge-piece in contact with a downwardly and forwardly facing, convexly curved, bearing surface of the overhanging portion of the bridge wall, thereby avoiding passage of air 35 between said bridge piece and the bridge wall. Owing to the intense heat to which the overhanging portion of the bridge wall is subjected, it is found that such curved bearing surface of the bridge wall tends to be 40 come roughened by corrosion or burning away, and also by the clinging of clinkers and ashes thereto, thereby producing an irregular surface. Such irregularity of the bearing surface, if caused by corrosion, permits 45 the passage of air between the bridge piece and bridge wall; or if caused by the adherence of clinkers to the wall prevents free movement of the swinging bridge piece relatively to the bearing surface of the wall. 50 In accordance with my present invention I propose to embody in the overhanging portion of the bridge wall a water-cooled member, preferably made of a metal tube, in contact with which the bridge member moves 55 when it is adjusted toward and away from

the upper surface of the grate, whereby is avoided the destructive action of the heat on the surface in contact with which the bridge piece is adjustably movable.

Furthermore, in my approved construction the bearing surface of the overhanging part of the bridge wall in contact with which the bridge piece moves during its adjustment, faces downwardly and rearwardly and the bridge piece swings upwardly and rearwardly away from the grate in contact with said bearing surface. This arrangement minimizes or entirely avoids the liability of clinkers and ashes clinging to said bearing surface of the bridge wall in a manner to interfere with the adjustment of the bridge piece.

In the accompanying drawings, I have shown my invention as applied to a furnace equipped with a traveling chain grate, and 75 have shown a bridge-piece substantially like that illustrated in my aforesaid application. Such construction is shown as merely illustrative of one practical embodiment of the invention.

The invention relates also to means for controlling the movement of the movable bridge piece in such manner as to maintain the desired thickness of the fuel bed and avoid the escape of unconsumed fuel from the grate.

As shown in the drawings:—Fig. 1 is a view in longitudinal vertical section of the rear end of a furnace and its bridge wall, showing in side view the rear portion of a traveling grate, and my water-cooled bridge 90 piece located between the grate and the overhanging portion of the bridge wall. Fig. 2 is an enlarged transverse, vertical section, taken on line 2—2 of Fig. 1, showing the parts constituting the principal elements of 95 my invention in elevation. Fig. 3 is a view similar to Fig. 2, but showing all the parts in section. Fig. 4 is an end elevation of the water-cooled bridge wall member. Fig. 5 is a section, taken on line 5—5 of Fig. 4. Fig. 100 6 is an external view showing the side wall of the furnace and a supporting plate by which are supported the ends of said bridge piece and bridge wall member, illustrating also the water connections for the water-cooled part. Fig. 7 is a vertical section, taken on line 7—7 of Fig. 2, looking in the direction indicated by the arrow. Fig. 8 is a fragmentary view similar to Fig. 6, showing a construction whereby the bridge wall is automatically 110

adjusted to coal beds of varying thicknesses. Fig. 9 is a partial section and a partial elevation of said parts.

As shown in the accompanying drawings, 5 A A¹ designate the side walls of a steam boiler furnace, B the rear or inner portion of a traveling chain grate, and A² a bridge wall which extends across the furnace at the rear of the grate and is provided with a projecting part A³ which overhangs the rear end of the grate.

C designates a tubular, water-cooled bridge piece which extends transversely across the furnace over the rear part of the 10 grate beneath the overhanging part A³ of the bridge wall and engages the lower portions of said overhanging part to close the space or opening between the bridge wall and the layer of fuel on the grate against the 15 passage of air. The bridge piece acts also to hold back or retard the passage of unconsumed fuel from the grate. The bridge piece C does not have contact directly with the refractory material constituting the 20 bridge wall, but engages a water-cooled member D constituting part of the overhanging portion of the bridge wall. Said water-cooled member D extends between 25 and is supported at its ends on the side walls 30 of the furnace. It is tubular and is provided with a convexly curved lower and rear bearing surface in contact with which the cylindric outer surface of the bridge piece moves during its adjustment toward 35 and from the grate. As herein shown, the bridge wall member is cylindric. The said tubular bridge piece and bridge wall member extend at their ends past the inner faces 40 of the side walls of the furnace into openings or recesses A⁴ A⁵ in said side walls of the furnace. The said bridge wall member D is stationary while the bridge piece C is bodily movable or capable of being shifted bodily 45 towards and from the grate, while maintaining its contact with the bridge wall member. In order to protect the water-cooled bridge wall member from the direct heat of the fire on the grate, the forwardly facing side and top of such member is embedded in the 50 overhanging portion of the bridge wall. As shown, said member is covered by a shield consisting of suitably shaped fire-brick D¹, the lower surface of which is concave to fit the convex surface of the bridge wall member. The said protecting shield extends at 55 its lower margin downwardly to the lower side of the bridge wall member D, and constitutes part of the overhanging portion of the bridge wall. The shield, as shown, consists of tiles of suitable length (Fig. 2), each tile being concave on its lower surface to fit the tubular bridge wall member, said tiles having on their forward sides depending portions or lips that fit in front of the tubular 60 bridge member and protect the front surface 65

thereof. The said shield tiles are made of a depth to fill the space between the bridge wall proper and the tubular bridge wall member. It will be furthermore observed that the water-cooled bridge member, which is supported at its ends in the side walls of the furnace, constitutes a support for the forward part of the overhanging portion of the bridge wall.

As a means of effecting bodily shifting of 75 the bridge piece relatively to the bridge wall member, said bridge piece is pivotally mounted at its ends in and sustained on the side walls of the furnace, so that it may swing or rotate in a curved path toward and from 80 the grate. The downwardly and rearwardly facing bearing surface of the bridge wall member is curved concentrically with respect to the pivotal axis of the bridge piece, thereby maintaining contact between the bridge 85 piece and the bridge wall member in all positions of adjustment of the former. The bridge piece herein illustrated swings about an axis which is located radially outside of its own diameter, so that said bridge piece is 90 swung or moved and slides around or over the bearing surface of the bridge wall member. The said pivotal mounting for the bridge piece is so constructed that the bridge piece swings rearwardly and upwardly or in a 95 direction away from the body of fuel on the grate. This arrangement avoids the tendency of the clinkers clinging to the bearing surface in contact with which the bridge piece moves.

The means shown for pivotally supporting 100 the bridge piece C are constructed as follows: At the outer side of the recess A⁴ is located a horizontal bearing sleeve E in which is rotatively mounted a trunnion c which is connected by means of a rigid offset arm c¹ with the adjacent end of the bridge piece C. As herein shown, said arm enters and has screw-threaded connection with the hollow bridge piece. E¹ designates a bearing plate for the 105 opposite end of the bridge piece, said plate being located at the outer face of the side wall A¹ and in position to close the recess A⁵. Said plate E¹ is fixed to a rectangular metal frame E² which is built in the recess A⁵ of the 110 wall A¹, said frame being provided at its top and bottom with inwardly extending flanges e² to which the bearing plate E¹ is bolted at its margins. This construction permits said bearing plate to be detached from the furnace 115 wall. Said bearing plate E¹ is provided with a bearing aperture e³ which is engaged by a journal or trunnion c³ extending outwardly from the offset arm C² at the adjacent ends 120 of the bridge piece. Said trunnion c³ is located in line with the trunnion c, and the arms are offset to bring the pivotal axis of the bridge piece concentric with the downwardly and rearwardly bearing surfaces of 125 the bridge piece, or in line with the longitudi- 130

dinal axis of the bridge piece when the latter is cylindric, as herein shown. Said trunnion c^3 and arm C^2 are made hollow to constitute a water passage which is in communication 5 with the interior of the tubular bridge piece through an opening c^4 . The arm C^2 is herein shown as made separate from the bridge piece and is flanged and bolted to a flanged ring c^5 having exterior screw-threaded engagement with the adjacent end of the bridge piece. The trunnion c^3 is extended outwardly beyond the bearing plate E^1 to form a nipple c^6 which is adapted at its outer end for attachment thereto of a supply pipe or 10 hose C^3 . Said nipple is provided adjacent to the trunnion c^3 with an angular or flat-sided part c^9 (Figs. 3, 6 and 7), adapted to receive the correspondingly shaped socket in the hub of a lever F by which a swinging or oscillatory movement may be imparted to the 15 bridge piece C .

The arm C^2 is formed to provide a passage c^{10} terminating in a neck c^{11} which constitutes a water passage that is in communication 20 with the interior of the bridge piece through a pipe c^{12} that extends into the hollow bridge piece and opens into the interior thereof near its end remote from the neck c^{11} . The said neck constitutes the inlet passage for the cooling agent, while the hollow arm and trunnions constitute the outlet passage. The pipe c^{12} is provided to deliver the cooling agent at a point remote from the outlet passage in order to maintain a circulation 25 of the cooling agent in said bridge-piece. Said neck c^{11} extends through a curved slot c^4 (Figs. 6 and 7) in the bearing plate E^1 , which is curved concentrically with respect to the bearing aperture c^8 of said plate, where- 30 by the neck swings through the slot during the adjusting movement of the bridge piece. To the outer end of the neck c^{11} is attached a second pipe or hose C^4 . A sliding segmental cover plate G is applied to the plate E^1 in a 35 manner as to cover the slot c^4 , as shown in Fig. 6. Said plate G is provided with an aperture through which said neck extends and is made longer than the slot so as to cover said slot in all positions of the neck c^{11} , as indicated most clearly in Fig. 6.

As shown in Fig. 6, the bridge piece is positively locked in a predetermined adjusted position, said locking means consisting of a pin f adapted to be inserted through a hole in the lever and any one of several holes f^1 in a segmental bar F secured to the outer face of the plate, and curved concentrically to the swinging axis of the lever.

In some instances, the bridge piece may be so mounted that it will automatically adjust itself to fuel and ash layers of varying thicknesses. One means of effecting this result is to attach a weight to the lever F in such manner that it acts together with the weight 65 of the bridge piece to hold the bridge piece

in its lowermost position. A thickening of the fuel bed has the effect, therefore, to automatically raise the bridge piece, while at the same time a pressure is maintained upon the fuel and ash layer that prevents the unburned fuel escaping beneath the bridge piece and prevents the passage of air between the bridge piece and fuel and ash layer. The latter suggested construction is shown in Figs. 8 and 9, and consists of a weight H carried by said lever F . As shown, the lever is provided with a plurality of apertures f^2 and the weight is suspended from the lever by a short cable h having a hook h^1 adapted to severally engage said apertures f^2 of the 70 lever.

From the construction described, it will be observed that by shifting the lever F the bridge piece C may be swung or adjusted on its pivotal axis to bring it into any desired 75 position with respect to the grate, and that during such adjusting movement, the bridge piece is maintained in contact with the water cooled member of the bridge wall. When the bridge piece is in its lowermost position, 80 as shown in full lines in Fig. 1, it is in contact with the lower face of the water-cooled member, and when swung away from the grate, as indicated in dotted lines in Fig. 1, it is located in rear of said water-cooled member. 85 By adjusting the bridge piece as described, its lower surface may be brought to a position at a greater or less vertical distance from the top surface of the grate and thereby vary the thickness of the layer of ashes which rests 90 on the grate beneath it.

Referring now to the manner of mounting said water-cooled bridge wall member at its ends in the side walls of the furnace, this construction is as follows: The water-cooled member is provided at its ends with offset or angular attaching arms D^2 D^3 which are inclined forwardly and upwardly (Figs. 1, 4 and 7) in said side wall openings A^4 A^5 so as to afford ample space for the offset arms of the bridge piece which are located exterior to the ends of the bridge wall member, and also to provide room for said arms to swing on their pivotal axis. The arm D^2 is flanged and is bolted to a flanged ring d surrounding 105 and having screw-threaded connection with the adjacent end of the tubular body of said water-cooled member. The outer end of the arm D^2 is formed to provide an angular stud d^2 which enters a socket in the side wall opening A^4 , thereby fixing said arm in place. The attaching arm D^3 , at the opposite end of the bridge wall member, is provided at its outer end with a narrow oblong stud or projection 110 d^3 which is adapted to fit within a correspondingly shaped opening in the removable plate E^1 and thereby hold said arm fixed to the plate. The attaching arm D^3 of said water-cooled member is provided with two passages d^4 d^5 , the former of which has direct 115

communication with the interior of said water-cooled member, and the latter of which has communication with said water-cooled member through a pipe d^6 that extends to 5 within a short distance of the end of said water-cooled member remote from the arm D^3 . The said passages d^4 d^5 communicate, respectively, with cooling agent supply and return pipes D^4 D^5 , as shown in Fig. 6. As 10 herein shown, the passages c^1 and d^6 of the arms C^2 and D^3 , respectively, of the bridge piece and water-cooled member of the bridge wall, constitute the inlet water passages which communicate with the supply pipes 15 C^4 D^5 leading from a common supply pipe D^6 , while the passages c^4 d^4 constitute the outlet passages and communicate with the outlet pipes C^3 D^4 that lead to a common outlet pipe D^7 . Inasmuch as the nipple c^1 and the neck 20 c^{11} associated with the bridge piece are movable, the pipes C^3 C^4 , communicating therewith, consists, in part, of flexible hose. The water-cooled bridge wall member being stationary, the pipes D^4 D^5 communicating 25 with the passages thereof may be made rigidly connected by stationary joints with said passages.

I claim as my invention:—

1. The combination with a traveling furnace grate and a bridge wall having a part 30 which projects forwardly over said grate, of a pivotally mounted, adjustable bridge piece between the wall and grate, the overhanging part of the bridge wall being provided with a 35 convexly curved, downwardly facing bearing surface adapted for contact with the bridge piece in all positions of the latter.

2. The combination with a traveling furnace grate and a bridge wall having a part 40 which projects forwardly over the grate, of a bridge piece extending transversely over the grate and provided at its ends with bearing trunnions by which the bridge piece is pivotally supported, the overhanging part of the 45 bridge wall being provided with a convexly curved, downwardly facing bearing surface adapted for contact with the intermediate portion of the bridge piece in all positions of the latter.

50 3. The combination with a traveling furnace grate and a bridge wall having a part which projects over said grate, including a water-cooled member, of a movably mounted bridge-piece in contact with the said water-cooled bridge wall member, and adapted to be shifted towards and from the grate while maintaining its contact with said bridge wall member.

60 4. The combination with a traveling furnace grate and a bridge wall having a part which projects over said grate, including a water-cooled member, of a bridge piece in contact with said water-cooled bridge wall member, said bridge piece being pivotally mounted to swing bodily towards and from

the grate while maintaining its contact with said water-cooled member.

5. The combination with the side walls of a furnace, a traveling grate and a bridge wall having a forwardly projecting overhanging 70 part, of a water-cooled member constituting a portion of said overhanging part of the bridge wall, and a pivotally mounted adjustable bridge piece in contact with said water-cooled member, said water-cooled member 75 having a convexly curved, downwardly facing bearing surface adapted for contact with the bridge piece in all positions of adjustment of the latter.

6. The combination with the side wall of a 80 furnace, a traveling grate and a bridge wall having a forwardly projecting overhanging part, of a tubular, downwardly facing member constituting a portion of the said overhanging part of the bridge wall, a pivotally 85 mounted, adjustable, tubular bridge piece located in contact with said tubular bridge wall member and adapted to maintain its contact therewith in all positions of adjustment of the bridge piece, and means for circulating a cooling agent through said tubular bridge piece and bridge wall member. 90

7. The combination with the side walls of a furnace, a traveling grate and a bridge wall having a forwardly projecting overhanging 95 part, of a water-cooled member constituting a portion of said overhanging part of the bridge wall, of a pivotally mounted bridge piece in contact with said bridge wall member, said bridge wall member having a convexly curved downwardly and rearwardly facing bearing surface adapted for contact with the bridge piece in all positions of adjustment of the latter, the bridge wall being 100 constructed to provide a shield for the forward side of said bridge wall member. 105

8. The combination with the side walls of a furnace, a traveling grate and a bridge wall, of a tubular water-cooled bridge wall member located in front of the bridge wall and fixed at its ends in the side walls of the furnace, and tiles which rest on the said tubular bridge wall member and fill the space between the latter and the bridge wall, said tiles being provided with depending lips extending in front of said bridge wall member. 115

9. The combination with the side walls of a furnace, a traveling grate and a bridge wall, of a tubular water-cooled bridge wall member located in front of the bridge wall and fixed at its ends in the side walls of the furnace, tiles which rest on said tubular bridge wall member and fill the space between the latter and the bridge wall, said tiles being provided with concave lower surfaces to fit the tubular bridge wall member, and an adjustable water-cooled bridge piece adapted to be bodily shifted relatively to the bridge wall member while remaining in contact therewith in all its positions of adjustment. 120 125 130

10. The combination with the side walls of a furnace, a traveling grate and a bridge wall having a forwardly projecting overhanging part, of a tubular water-cooled bridge wall member located beneath said overhanging part of the bridge wall and fixed at its ends in the side walls of the furnace, tiles interposed between said overhanging part of the bridge wall and the tubular bridge wall member, said tiles being provided with concave lower surfaces to fit the tubular bridge wall member, and with depending lips extending in front of said bridge wall member. 65
11. The combination with the side walls of a furnace, a traveling grate and a bridge wall having a forwardly projecting overhanging portion, of a tubular water-cooled bridge wall member, extending across the furnace and fixed at its ends in said side walls and supporting the said overhanging part of the bridge wall, and an adjustable water-cooled bridge piece adapted to be bodily shifted relatively to the bridge wall member while remaining in contact therewith in all its positions of adjustment. 70
12. The combination with a bridge wall, including a tubular water-cooled member, of a pivotally supported, adjustable water-cooled bridge piece adapted to be bodily shifted relatively to the bridge wall member, while maintaining contact therewith. 75
13. The combination with the side walls of the furnace, a traveling grate and an overhanging bridge wall, including a tubular water cooled member supported at its ends in the side walls of the furnace, of an adjustable bridge-piece in bearing contact with said bridge wall member, and provided at its ends with offset arms having trunnions rotatively mounted in said side walls concentrically with the exterior bearing surface of said bridge wall member. 80
14. The combination with a traveling grate and a bridge wall, including a tubular water-cooled member, of a pivotally supported, adjustable water-cooled bridge piece adapted to be bodily shifted relatively to the bridge wall member, while maintaining contact therewith, and an adjustable weight acting with the weight of the bridge piece tending to hold the bridge piece in its lowermost position. 85
15. The combination with the side walls of the furnace, a traveling grate and an overhanging bridge wall, including a tubular water cooled member supported at its ends in the side walls of the furnace, of an adjustable bridge piece in bearing contact with said bridge wall member and provided at its ends with offset arms having trunnions rotatively mounted in said side walls concentrically with the exterior bearing surface of said bridge wall member. 90
16. The combination with a traveling grate and a bridge wall including a tubular metal member, of a tubular bridge piece in contact with said bridge wall member and adapted to be bodily shifted relatively to the bridge wall member while maintained in contact therewith and water supply and return passages connected with said tubular bridge-piece and bridge wall member. 95
17. The combination with the side walls of a furnace and a traveling grate, of a bridge wall provided with an overhanging part, including a water-cooled member, of a swinging water-cooled bridge piece in contact with the water-cooled bridge member and having trunnions at its ends which are mounted in the side walls of the furnace. 100
18. The combination with the side walls of a furnace a traveling grate and its overhanging bridge wall, including a tubular, water-cooled member supported at its ends in the side walls of the furnace, and having a cylindric bearing surface, of an adjustable bridge-piece in bearing contact with said bridge wall member and provided at its ends with offset arms having trunnions rotatively mounted in said side walls concentrically with the exterior bearing surface of said bridge wall member. 105
19. The combination with the side walls of a furnace, a traveling grate and a bridge wall having an overhanging part, of a tubular, water-cooled member supported at its ends in the side walls of the furnace and constituting a portion of said overhanging part of the bridge wall, and an adjustable bridge piece in bearing contact with said bridge wall member and provided at its ends with offset arms having trunnions rotatively mounted in said side walls in line with the central longitudinal axis of the bridge wall member. 110
20. The combination with the side walls of a furnace, a traveling grate and a bridge wall having an overhanging part, of a tubular water-cooled member constituting a portion of the overhanging part of the bridge wall, a bridge piece in contact with said bridge wall member provided at its ends with offset arms having trunnions which are rotatively mounted in said side walls, said offset arms extending upwardly between the ends of said bridge wall member and the bearing supports for the trunnions, and the bridge wall member having end offset arms by which it is fixed in said side walls. 115
21. The combination with the side walls of a furnace, a traveling grate and a bridge wall having an overhanging part, of a tubular water-cooled member constituting a portion 120

of said overhanging part of the bridge wall, and a bridge piece in contact with said bridge wall member provided at its ends with offset arms having trunnions which are rotatively mounted in said side walls, said offset arms extending upwardly between the ends of said bridge wall member and the bearing supports for the trunnions and the bridge wall member having end offset arms by which it is fixed in said side walls, said offset arms of

the bridge piece and bridge wall member being located in different planes.

In testimony, that I claim the foregoing as my invention I affix my signature in presence of two witnesses, this 21st day of February 15 A. D. 1906.

JOSEPH HARRINGTON.
